(57) **CLAIM**

The ornamental design for an acoustical isolator, as shown and described.

DESCRIPTION

FIG. 1 is a top perspective view of an acoustical isolator; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom side view thereof.

The broken line showing of an acoustical isolator is included for the purpose of illustrating environmental structure only and forms no part of the claimed design.
